UNITED STATES PATENT OFFICE

CHESTER C. MARTIN, OF LUCKEY, OHIO, ASSIGNOR, BY MESNE ASSIGNMENTS, TO ST. REGIS PAPER COMPANY, OF NEW YORK, N. Y., A CORPORATION OF NEW YORK

VALVE BAG

Application filed September 3, 1926. Serial No. 133,336.

This invention relates to valve bags, and more particularly to paper valve bags intended for comparatively light materials.

The purpose of the invention is to provide a bag which may be filled through a valve in a well known manner, and securely closed so that there will be no leakage through the valve.

In the accompanying drawings forming a part of this specification, Figure 1 is a view of one end of a bag embodying my invention and broken away to more clearly disclose the construction; Fig. 2 is an end view of the valve end of the bag before it is filled; Figs. 3 and 4 are somewhat diagrammatic views indicating the manner in which the valve is sealed against leakage.

In the construction shown, a bag 10 is disclosed having the usual valve flap 11, between which and the end flaps the feed pipe 12 enters the bag, the bag being filled through the opening 13 at the end of the feed pipe. This is in accordance with the well-known construction and operation of such bags.

In accordance with my invention there is a tube 14, preferably of fairly stiff paper, inserted into the valve opening. This tube is affixed to the inner end of valve flap 11, as by means of adhesive 15. The opposite side of the tube is affixed to the end flap, as by means of adhesive 16. In the construction shown, adhesive 16 does not extend all the way between the end flap and the tube, leaving a free space, as at 17, between the tube 14 and the end flap 18.

The outer end 19 of tube 14 extends sufficiently far so that it can be folded after the bag is filled, as shown in Figs. 3 and 4. Preferably, the tube is first flattened, then the corners 20 are folded in the manner shown in Fig. 3, and then the end of the tube is folded over and tucked under end flap 18, as shown in Fig. 4. If preferred, the folded end of tube 14 might be folded under against valve flap 11, but it is considered preferable to insert it beneath the end flap in the manner shown.

This manner of closing the valve may be used in any valve bag where the slight amount of leakage which normally occurs through a

valve is objectionable. One particular use for which it has been found suitable is the secure closing of comparatively small paper valve bags in which light material, such as lime, is packaged. The lighter material does not close a paper valve as securely as heavy material. Where these small bags are to be handled in such a way that any leakage is objectionable, as where they are handled through grocery stores, etc., it is desirable to securely seal the valve. This is accomplished, particularly where the tube 14 is sufficiently stiff so that it retains its folded position with certainty.

It will be understood that, while one form of bag and valve-sealing tube has been disclosed in detail, various modifications may be made within the scope of the appended claims.

What I claim is:

1. A bag ready for filling and having a valve opening, a valve-sealing tube open at both ends and having its inner end affixed in the valve opening and having its outer end extending outward from said opening and designed to form a sealing closure at said outer end.

2. A bag having a valve opening, a valve-sealing tube open at both ends and having its inner end affixed to the inside of the walls of the valve and having its outer end extending far enough to fold, there being a space between the tube and the outer edge of the valve adapted to receive the folded end of the tube.

3. A paper valve bag having its valve formed by end flaps, and a paper valve-sealing tube open at both ends and inserted between the valve forming flaps and adhered to said flaps at its inner end, the outer end of the tube extending outward far enough to fold, and there being a space between the outer edge of the end flap and the tube wherein the folded end of the tube may be inserted.

In testimony whereof I have hereunto signed my name to this specification.

CHESTER C. MARTIN.
